DRINKING FOUNTAIN ATTACHMENT

Edward P. Tyler, North Hollywood, Calif.

Application March 31, 1947, Serial No. 738,338

2 Claims. (Cl. 299—9)

1

The present invention relates to drinking fountains, particularly to one which may be easily attached to a faucet for the purpose of directing the water into two paths, to wit: either directly downwardly from the faucet or upwardly at an angle.

The invention has for an object the provision of means which assures that the drinking of water by a plurality of individuals will not cause contamination of the device, in that the water is directed outwardly therefrom for drinking purposes, the lips not touching any portion of the device. The ordinary drinking glass used in public places is a notorious carrier of germs, and such diseases as trench mouth are easily communicated where a common glass is used by many people.

A further object of the invention is the provision of a drinking fountain so formed and constructed as to allow its ready attachment to the ordinary faucet as generally found both within and without houses, which when so positioned on the faucet will not interfere with direct water flow if such direct flow is desired.

A further object is the provision of a drinking fountain incorporating a novel form of valve which when actuated in one direction will permit water to be deflected upwardly at an angle and under a selected pressure, any excess of water pressure permitting the water to be directed downwardly past the valve.

Other objects include a drinking fountain attachment which is inexpensive in cost to manufacture, attractive in appearance, useful for a variety of purposes, and which is generally superior to devices now known to the inventor.

In the drawing:

Fig. 1 is a side elevation of the drinking fountain shown attached to a faucet;

Fig. 2 is a vertical sectional view on the line 2—2 of Fig. 5 showing the valve member of the device in one position;

Fig. 3 is a sectional view similar to that of Fig. 2, the valve being moved to a second position;

Fig. 4 is a sectional view on the line 4—4 of Fig. 3;

Fig. 5 is a view looking in the direction of the arrow 5 of Fig. 3; and

Fig. 6 is a bottom plan view looking in the direction of the arrow 6 of Fig. 3.

Referring now to the drawing:

The improved drinking fountain is designated as an entirety and in one embodiment by the numeral 1, and said drinking fountain is shown as frictionally secured to a faucet 2 and specifically

2

ly the spout 3 thereof. The drinking fountain may be formed of resilient material such as rubber or rubber composition, or in certain circumstances, of a plastic, and the same includes a body 4, provided with a central bore 5, and with a bore 6 communicating with the central bore. That portion of the body containing bore 6 constitutes what may be termed a spout 7, which is molded or otherwise secured to the body 4. The bore 5 is not uniform in diameter, being provided with an enlarged counterbore portion at 8, a reduced counterbore at 9, and an enlarged counterbore at 10. The reduced counterbore portion 9 is intermediate counterbores 8 and 10. The construction is such that a flange or lip 11 overlies counterbore 8. This portion forms the entrance way for receiving the spout 3.

A flap valve 12 is secured by a narrow tongue 13 to the body 4 within the bore 5, and specifically 20 at that portion which lies between the counterbores 9 and 10. The flap valve is preferably circular, and is of a diameter sufficient to span the counterbore 9 when the flap valve is in an upward position, or the position shown in Fig. 2. 25 The bore 6 of spout 7 communicates both above and below the flap valve 12 when the valve is bridging counterbore 9, see Fig. 2.

Means 14 is provided for swingingly actuating the flap valve from the position of Fig. 2 to that 30 of Fig. 3. The said means 14 in the present instance includes a wire which is looped at one end 15, with a portion 16 which substantially parallels the side of the body 4, and a portion 17 at an angle to portion 16, which portion has a 35 U-shaped bend at 18, finally terminating in part 19 in axial alignment with part 17. The body is transversely bored at 20 to accommodate portions 17 and 19 and position the U-shaped portion 18 adjacent the top of the flap valve 12.

In the embodiment of the invention shown, the outer surface of the body 4 is tapered, and the spout 7 extends from one side of the body, as best illustrated in Figs. 1 and 5. This construction enhances the appearance of the device. In 45 the embodiment shown the bore 6 is shown as being of two diameters in that the bore portion at 21 is of smaller diameter than the bore portion which communicates with the central bore of the body. Such a construction aids in over-50 coming back pressure, and likewise permits the small stream to rise to a certain height above the fountain when the fountain is being used.

The operation, uses and advantages of the invention just described are as follows:

55 Preferably the drinking fountain is formed of

rubber or rubber composition, although as previously stated it may be formed of other materials. The device is adapted to have a frictional engagement with the spout 3 of the faucet 2, and the spout 3 is positioned in the center bore approximately to the zone lying between the counterbores 8 and 9. The lip or flange 11 will tightly grip the surface of the spout 3 and aid in preventing any leak of water. When the valve of the faucet is opened the water will impinge against the flap valve 12 which normally transversely spans or bridges counterbore 9. This flap valve acts to deflect water into bore 6 of spout 7. There is no need to completely open the faucet when the device of the invention is being used as a drinking fountain, as such excess pressure will only deflect the flap valve further downwardly. The flap valve 12, together with its tongue 13, has sufficient stiffness to assure that it is not easily deflected under ordinary water pressure. When the flap valve is in a position such as shown at 22, water will not only move upwardly through the bore 6 of the spout, but part of the flow will be directed through bore 10. However the water which is deflected upwardly through bore 6 will rise several inches above the spout 7. If the spout 7 is not to be used, the means 14 may be moved by pushing upon the loop 15, the U-shaped portion 18 engaging the top surface of the flap valve and swinging it downwardly to the position shown in Fig. 3. In this position the flap valve does not interfere with the flow of water through the bore 5 and water will flow normally, that is straight downwardly. In Fig. 2, the means 14 has been moved from the position shown at 23 to that of 24, which would move the valve to the position shown at 22. Obviously movement of the means 14 will regulate the height to which water will rise above spout 7.

The present device takes advantage of certain principles in the flow of water in that the end of the spout 3 would normally engage the shoulder 25, which is formed by the difference in diameter between the counterbores 8 and 9. Thus the lower end of the spout 3 is sealed at this zone. The counterbore 9, by being reduced in diameter, will cause an increase in the speed of flow of the water, assuming the same pressure, while the portion 10, by being enlarged in diameter, that is, of greater diameter than the portion 9, will effect a reduced flow of water at this point. Thus the flap valve 12 is found to function efficiently, due to the enlarged area therebeneath, with the ultimate object in view of

permitting the flap valve to deflect water into bore 6 of the spout 7. This construction permits the drinking fountain to function more efficiently than it would if the through bore 5 was of uniform diameter. The through bore 5 constitutes what may be termed an open-ended passageway in the body 4.

I claim:

1. A drinking fountain attachment for a faucet, including a body formed with a through bore having upper and lower counterbores of one diameter and an intermediate counterbore of lesser diameter, and formed with a bore at an angle to the axis of the aforementioned bores, said last named bore communicating with the lowermost counterbore in the body, a resilient flap valve interposed between the counterbore of lesser diameter and the lowermost counterbore; and means for positively moving the flap valve from a horizontal position to a position at an angle to the axis of the through bore.
2. A drinking fountain attachment for a faucet, including a body of resilient material formed with a throughbore and with a bore communicating with the throughbore and at an angle to said throughbore, a resilient flap valve integrally formed within the body and bridging the throughbore at the zone of its confluence with the second-named bore, and a wire transversely passed through said body above the resilient flap valve and provided with a U-shaped bend adapted, when said wire is rotated, to engage the flap valve, the said wire having an external portion providing a handle, rocking movement of the handle causing the U-shaped bend to depress the valve from a horizontal position to a position at an angle to the axis of the throughbore.
